UNITED STATES PATENT OFFICE

ATTILIO R. PASCUCCI, OF PROVIDENCE, RHODE ISLAND, ASSIGNOR TO HAVERHILL SHOE NOVELTY COMPANY, OF HAVERHILL, MASSACHUSETTS, A CORPORATION OF MASSACHUSETTS

DESIGN FOR A SHOE ORNAMENT

Application filed October 17, 1930. Serial No. 37,282. Term of patent 7 years.

To all whom it may concern:

Be it known that I, ATTILIO R. PASCUCCI, a citizen of the United States of America, residing in Providence, in the county of Providence and State of Rhode Island, have invented a new, original, and ornamental Design for Shoe Ornament, of which the following is a specification, reference being had to the accompanying drawings, forming part thereof.

Fig. 1 is a plan view of a shoe ornament showing my new design; and

Fig. 2 is an edge view of the ornament.

I claim:

The ornamental design for a shoe ornament as shown.

Signed by me at Providence, in the county of Providence and State of Rhode Island, this 22nd day of September, 1930.

ATTILIO R. PASCUCCI.
